MODEL FOR GEOMETRY INSTRUCTION

Filed May 10, 1928

UNITED STATES PATENT OFFICE

JEAN GUYER, OF ZURICH, SWITZERLAND

MODEL FOR GEOMETRY INSTRUCTION

Application filed May 10, 1928, Serial No. 276,737, and in Germany June 11, 1927.

This invention relates to a model more particularly adapted for use in instruction in perspective geometrical drawing in schools, colleges and other institutions.

- 5 One object of the invention is to provide a geometry model in which geometrical identities such as diagonals, heights and cross-sections may be readily demonstrated and shown.
- 10 Another object of the invention is to provide a geometry model comprising detachable and interchangeable component parts which may be assembled in frame-like manner.
- 15 A still further object is to provide a geometry model which is easily assembled and is so light as to be readily carried from place to place.

In the drawings:—

- 20 Fig. 1 is a perspective of a model of a four-sided pyramid constructed in accordance with this invention.

Fig. 2 is a detail section of the apex-piece.

- 25 The pyramid shown in Fig. 1 comprises eight straight rods, four spherical connector members and one detachable apex-piece 10 (Fig. 2). Elastic cords *a* are provided to demonstrate the lateral dimensions of the base of the pyramid, and elastic cords *b* represent a horizontal section of the pyramid and pass over, or are fixed to, sleeves 14 which are slidably arranged on rods *c* representing the upper surface edges of the pyramid. A non-elastic cord 12 is provided to demonstrate the height of the apex from the base of the pyramid.
- 30
- 35

The apex-piece connector member is provided with a sufficient number of holes for the reception of the rods. These holes are all of the same diameter and are disposed at the correct angular relationship to each other as required for the construction of the models.

What I claim is:

- 40 In apparatus of the class described, rods arranged at an angle to one another, sleeves slidable on the rods and an elastic cord connecting the sleeves together.
- 45

In testimony whereof I affix my signature.
JEAN GUYER.
